(57) **CLAIM**

The ornamental design for a plasma array connector device, as shown and described.

DESCRIPTION

FIG. 1 is an isometric view of a front, top, and left side of an ornamental design for a plasma connector device.

FIG. 2 is an isometric view of a rear, bottom, and left side of the device of FIG. 1.

FIG. 3 is a top view of the device of FIG. 1.

FIG. 4 is a bottom view of the device of FIG. 1.

FIG. 5 is a left side view of the device of FIG. 1.

FIG. 6 is a right side view of the device of FIG. 1.

FIG. 7 is a front side view of the device of FIG. 1.

FIG. 8 is a rear side view of the device of FIG. 1.

FIG. 9 is an isometric view of a front, top, and left side of the device of FIG. 1 connected to a plasma array.

FIG. 10 is an isometric view of a rear, bottom, and left side of the device of FIG. 1 connected to a plasma array.

FIG. 11 is a top view of the device of FIG. 1 connected to a plasma array.

FIG. 12 is a bottom view of the device of FIG. 1 connected to a plasma array.

FIG. 13 is a left side view of the device of FIG. 1 connected to a plasma array.

FIG. 14 is a right side view of the device of FIG. 1 connected to a plasma array.

FIG. 15 is a front side view of the device of FIG. 1 connected to a plasma array; and,

FIG. 16 is a rear side view of the device of FIG. 1 connected to a plasma array.

The dash-dash-dash lines are included for the purpose of illustrating portions that form no part of the claimed design.
